DESIGN FOR A CANDLESTICK

A. Jay Ackerman, Warren, Conn., assignor to New Martinsville Glass Manufacturing Company, New Martinsville, W. Va., a corporation of West Virginia

Application February 26, 1940, Serial No. 90,509

Term of patent 3½ years

To all whom it may concern:

Be it known that I, A. Jay Ackerman, a citizen of the United States, residing at Warren, in the county of Litchfield and State of Connecticut, have invented a new, original, and ornamental Design for a Candlestick, of which the following is a specification, reference being had to the accompanying drawing, forming part thereof.

Of the drawing:

Fig. 1 is a side elevational view of a candlestick embodying my new design.

Fig. 2 is an elevational view of one end of the candlestick.

Fig. 3 is a top plan view of the candlestick.

Fig. 4 is an end elevational view of the other end of the candlestick.

I claim:

The ornamental design for a candlestick, as shown.

A. JAY ACKERMAN.
